UNITED STATES PATENT OFFICE.

CHARLES L. McDONAL, OF MONTICELLO, MISSISSIPPI, ASSIGNOR OF ONE-HALF TO
JAMES W. PENINGTON, OF BROOKHAVEN, MISSISSIPPI.

SPRING-MOTOR.

1,212,782.

specification of Letters Patent. Patented Jan. 16, 1917.

Application filed March 31, 1916. Serial No. 88,077.

To all whom it may concern:

Be it known that I, CHARLES L. McDONAL, a citizen of the United States, residing at Monticello, in the county of Lawrence and 5 State of Mississippi, have invented certain new and useful Improvements in Spring-Motors, of which the following is a specification.

This invention relates to motors and 10 more particularly to that class of motors wherein a spring serves as the prime mover.

The primary object of the invention is to provide a motor of the character described, which may be adapted to propel or operate 15 various constructions, and in this particular instance, I preferably employ the same as means for rotating a churn dasher, thereby minimizing the heretofore laborious work 20 associated with the operation of such devices.

The invention contemplates a main drive shaft having positioned thereupon and affixed thereto the propelling spring, said 25 drive shaft having keyed thereto, a master, or drive gear, which is, through the medium of a train of gears, adapted to impart a rotary motion to a vertically disposed shaft, which is adapted to receive the upper end 30 of the churn operating handle; further, to mount upon one of the horizontally arranged shafts used in conjunction with the gearing, a rotary fan, for the convenience of the operator.

It is also among the aims and objects of 35 the invention to provide a signal or alarm mechanism, which mechanism is so actuated as to operate a signal when the propelling spring has unwound to a predetermined extent; also, to provide a controlling handle 40 whereby the movement of the propelling spring may be minutely regulated.

The improvements in the details and arrangement of the parts will be apparent from an inspection of the accompanying 45 drawings, in connection with the specific description hereinafter contained, and wherein the preferred embodiment of the invention is disclosed for the purpose of im-

parting a full understanding of the invention.

In the drawings;—Figure 1 is a side elevation; Fig. 2 is a longitudinal section in elevation; Fig. 3 is a transverse section taken on the line 3—3 of Fig. 1; Fig. 4 is a detail in section of the means for actuating the signal; and Fig. 5 is a detail in perspective of the means for moving the signal actuating member into operative relation with the signal.

Referring now to the drawings wherein 60 like characters designate like or corresponding parts throughout the several views, and in which 1 designates a supporting frame in entirety said frame comprising side and end portions 2 and 3, respectively, which 65 have secured thereto at each of the four corners as provided by the end and side pieces, vertically disposed supporting legs generally numbered 4. Arranged adjacent the side pieces 2 and affixed thereto, are vertically disposed gearing supporting standards 5 and 6 while secured to and supported by one of the side pieces 2 is a right angularly disposed bracket arm 7, the purpose of 70 which shall be hereinafter described. Positioned between the vertical supporting standards 5 and 6 and journaled in suitable bearings, provided for in the side pieces 2 is a transversely arranged shaft 8, said shaft 75 having a squared end portion, as at 9, and having arranged thereupon and keyed thereto a driving gear 10, which gear has positioned adjacent thereto and secured to the same, in the conventional manner, as common to this particular art, a 80 propelling spring 11, which may be in the form of the ordinary coiled spring invariably used for such purposes. Arranged above said transverse shaft 8 and preferably 85 in vertical alinement therewith, is a transverse shaft 12, which shaft, has arranged thereon and keyed thereto a driven gear 13 and a driving gear 14, the latter being of a diameter greater than the former. The shaft 12 is provided with an elongated extension, as designated at 15, which shall be 90

95

subsequently described. Positioned above the shaft 12 and journaled within the supporting standards 5 and 6 is a similar shaft 16, which shaft has arranged thereon and 5 keyed thereto driven and driving gears 17 and 18, constructed in accordance with the gears 13 and 14, while arranged above the shaft 16 and also journaled within suitable bearings in the supporting standards 5 and 10 6 is a transversely arranged shaft 19, this shaft being of a greater length than the shafts 12 and 16 and having keyed thereto a driven gear 20, a balance wheel 21, a beveled gear 22, and a rotary fan 23, the fan 15 being positioned at the extreme outer end of said shaft.

In order to provide for auxiliary supporting means whereby the beveled gears 22 may be rigidly supported, I provide an 20 angularly disposed bracket 24, which is secured to the vertical supporting standard 6, by suitable fastening devices. Positioned on a suitable bearing arranged in the bracket arm 7 is a vertically disposed shaft 25, which shaft extends upwardly and has arranged on its upper end and keyed thereto a beveled gear 26, which is constantly meshed with the beveled gear 22, while the lower end of the shaft 25 has arranged 30 thereon a circular member 27, which serves to support flexible members 28, these members serving as means for shooing flies away, while the end of the shaft is preferably made hollow, to receive the operating 35 handle 29 of a churn dasher 30, which dasher is mounted within the usual receptacle 31, used in conjunction with churns. The operating handle or rod 29 is secured within the hollow or socket portion of the 40 shaft 25 by means of a cotter pin 32, which is passed therethrough. Pivotaly supported as at 33, upon one of the side members 2, is a controlling arm 34, which normally engages with the gear teeth of the driving 45 gear 10, and is provided with a handle portion 35, which portion is adjustably received by the teeth of a rack 36 which is secured to one of the end pieces 3 as at 37.

In devices of this character, it is highly 50 desirable to provide for signaling means for indicating when the spring motor has become unwound, and to this end I provide a substantially bell crank lever 38, which is pivotally mounted between ears 39 carried 55 by the vertical supporting standard 6, and extends through an opening 40 arranged adjacent thereto in the said standard 6 into close proximity with the driving spring 11, while the upper end of the lever 38 is provided with a right angularly distended arm 60 41, having a portion 42 bent at angles thereto as shown to advantage in Fig. 5, which portion 41 is adapted to engage with a star wheel 43, splined to the elongated extension 65 of the shaft 12, as at 44, thereby causing

said star wheel to be moved outwardly. Arranged above the shaft 12 and supported by the vertical standard 6, is a distended supporting arm 45, which arm has pivotally secured thereto a bell striking hammer 46, which is adapted to strike a bell 47, also suitably mounted upon the vertical supporting standard 6. 70

Means may be provided whereby the shaft 8 may be rotated so as to wind the spring 75 11, thereby providing for the necessary tension, in form of a crank handle 48.

The operation of the device is as follows: assuming that the spring 11 has been wound and that the controlling lever 34 has been 80 disengaged from the driving gear 10, it will be seen that motion will be imparted to the shaft 19 by means of the train of gearing, thus rotating the fan 23 and the beveled gear 22, which gear due to the fact that it is meshed with the beveled gear 26 upon the vertically disposed shaft 25, will rotate said shaft 25, which motion will be imparted to the dasher 30 also causing the fly shooing arrangement to be operated. Upon continued rotation of the driving wheel pin the spring 11 will be unwound, consequently causing the same to expand and to engage that portion of the bell crank lever 38 which extends into its path, causing the bell crank lever with its projection 41 to be moved forwardly, thus moving the star wheel 43 and causing the same to engage with the bell striking hammer 46, intermittently operating the same and causing the bell 47 to 90 be rung, whereby the attention of the operator may be attracted and the crank 48 may be applied to the square end of the shaft 8 whereby the spring 11 may be rewound for a subsequent operation. 95

In accordance with the provisions of the patent statutes, I have described the preferred embodiment of my invention, together with apparatus which I now consider to represent the preferred form of my 100 invention, but I desire to have it understood that the same is only illustrative and that different arrangement of the parts from those shown and described may be resorted to together with mechanical equivalents for 105 some or all of said parts as may be in keeping with the hereto appended claims. 110

I claim:

1. In a spring motor, a counter-shaft arranged adjacent the driving shaft of the 115 motor and intergeared therewith, an audible signal arranged in proximity with said counter-shaft, signal operating means movably mounted upon the counter-shaft, and a lever arranged upon the motor frame engageable with said operating means and the motor spring for moving the operating means into position for operating the audible signal upon expansion of the motor 120 spring. 125

2. In a spring motor having a counter-shaft arranged adjacent the driving shaft thereof and intergeared therewith, an audible signal arranged in proximity to said counter-shaft, a hammer for said signal, a star wheel slidably mounted upon the counter-shaft engageable at times with said hammer, and a lever arranged upon the motor frame engageable with said star wheel and the motor spring for moving the

star wheel into position for engaging the hammer upon expansion of the motor spring.

In testimony whereof I affix my signature in presence of two witnesses.

CHARLES L. McDONAL.
